UNITED STATES PATENT OFFICE.

LEVI HEYWOOD, JOSEPH L. ROSS, AND JAMES K. OTIS, OF BOSTON, MASSACHUSETTS.

PORTABLE BUREAU.

Specification of Letters Patent No. 11,551, dated August 22, 1854.

To all whom it may concern:

Be it known that we, LEVI HEYWOOD, JOSEPH L. ROSS, and JAMES K. OTIS, all of Boston, in the county of Suffolk and State 5 of Massachusetts, have invented certain new and useful Improvements in Portable Bureaus or Cases of Drawers, and that the following description, taken in connection with the accompanying drawings, hereinafter referred to, forms a full and exact specification 10 of the same, wherein we have set forth the nature and principles of our said improvements by which our invention may be distinguished from others of a similar class, 15 together with such parts as we claim and desire to have secured to us by Letters Patent.

The figures of the accompanying plates of drawings represent our improvements.

20 In Plate 1, Figure 1 is a front elevation of the bureau when set up, and Fig. 2, a horizontal section of the same taken in the plane of the line A B, Fig. 1. In Plate 2, Fig. 3 is a transverse vertical section of the 25 bureau taken in the plane of the line C D, Fig. 1. Figs. 4 and 5 are detail sectional views which will be hereinafter referred to. In Plate 3, Fig. 6 is a plan or top view of the bureau, dismembered, with the different 30 pieces packed in a box, and Fig. 7 is a transverse vertical section of the same, taken in the plane of the line E F, Fig. 6. Fig. 8 is a rear elevation of the bureau drawn to a reduced scale.

35 Our improvements are made upon that class of bureaus or cases of drawers, which are susceptible of dismemberment, and are designed to facilitate the process of taking apart and putting together the different 40 pieces of which the bureau is composed, and also to economize the space occupied by the parts when packed for transportation. These results we effect by forming an independent frame or case which receives all 45 the side pieces which form the drawers, the whole bureau being supported and rigidly held together when set up, by a peculiarly constructed back, which also serves, when the bureau is dismembered, for a bottom to 50 the frame or case which receives the different pieces of the drawers.

55 a a—a a represent the two ends of the bureau which are connected together at the back by two cross bars b, b which are dove-tailed into a projection of the said end pieces as shown in Fig. 4, Plate 2.

b' b''—c c are the side and end pieces of the base of the bureau dove-tailed into each other as shown in Fig. 5, Plate 2.

e e e e is an independent frame or case, 60 with cross bars f, f, f, which rests upon the base of the bureau and is fastened to the same by screws g, g. This frame extends out flush with the front of the bureau and back as far as the rests j, j, &c., on which 65 the drawers run.

h h is the top of the bureau and is fastened by screws i, i, i, i to the upper cross bar b, before referred to, and to the top bar of the frame e e e e. 70

k k is an ornamental piece attached by screws to the back of the top h h.

l, l, l, l are the front, back and end pieces which form each drawer, dove-tailed into each other. m, m, &c., are the bottoms of 75 the drawers which are also connected to the pieces l, l by dove-tails, or tongues and grooves. The back of the bureau is composed of sectional pieces or panels n, n, n, n, which enter proper grooves formed in the 80 diagonal cross braces o o—o o, (shown by red lines in Fig. 1, Pl. 1, and in section in Fig. 2, Pl. 1, and Fig. 3, Pl. 2). The whole back thus formed, is fastened to the end pieces a a—a a by screws. The back thus 85 formed of the diagonal cross braces, which are lapped into each other at their intersection, and of sectional pieces or panels, effectually holds the whole body of the bureau rigidly together, which is very essential 90 in a bureau susceptible of dismemberment. In a back constructed in the ordinary manner, its construction and expansion would materially affect the other parts of the bureau, and displace them, but in this 95 peculiar form of back the contraction or expansion of the sectional pieces or panels n, n &c., cannot disarrange the other portions of the bureau, while the diagonal braces serve to strengthen and bind the 100 whole firmly together.

The bureau is taken apart by removing the screws before referred to and slipping the different pieces out of their grooves or dove-tails, the whole frame e e e e with its 105 cross bars, being taken out entire, and having the back o o—n n fastened to it to serve as a bottom to the same, the front, back, and end pieces l, l, l, l being disjointed and placed in the compartments of the case thus 110 formed by the frame e, e, e, e, its cross bars f, f, f and the back o o—n n, as shown in

Figs. 6 and 7, Pl. 3. The end pieces, *a a*—*a a*, the top piece *h h*, and base *b b*—*c c*, are arranged in the packing box *p p*, in the relative positions shown by red lines in Fig. 6, 5 Pl. 3 and in section in Fig. 7, Pl. 3, the bottoms *m m* of the drawers (represented as removed in Fig. 6,) being placed at the top of the box *p p*, and resting immediately upon the frame *e e e e*.

10 From the above description it will be seen that the different pieces which compose the bureau can be readily fastened together (no glue being used) or taken apart, and that when set up, the diagonally braced back 15 maintains the strength and rigidity of the whole, and also serves as a back to the independent frame, when the bureau is in pieces. The bureau also, when dismembered, occupies but very little space in the 20 packing box, as the front, back and end pieces of each drawer, are packed together in the same compartment of the independent frame, in which they slide when put together, and this arrangement is peculiarly

convenient, as there will be no difficulty in 25 finding and putting together the pieces which belong to each drawer.

Having thus described our improvements we shall state our claim as follows:

What we claim as our invention and desire to have secured to us by Letters Patent is,—

Forming in a bureau or case of drawers which is susceptible of dismemberment an independent frame or case, which, when the 35 parts are disjointed and the back of the bureau attached to it, serves as a box or case to receive the front, back and end pieces of each drawer, the pieces which compose each drawer being packed in the same compartment of this independent frame, in which the 40 said drawer slides when put together.

LEVI HEYWOOD.
JOSEPH L. ROSS.
JAMES K. OTIS.
